UNITED STATES PATENT OFFICE.

HENRY G. VOIGHT, OF NEW BRITAIN, CONNECTICUT, ASSIGNOR TO RUSSELL & ERWIN MANUFACTURING COMPANY, OF NEW BRITAIN, CONNECTICUT, A CORPORATION OF CONNECTICUT.

CYLINDER-LOCK CONSTRUCTION.

1,002,098.

Specification of Letters Patent. Patented Aug. 29, 1911.

Application filed May 19, 1911. Serial No. 628,243.

To all whom it may concern:

Be it known that I, HENRY G. VOIGHT, a citizen of the United States, residing at New Britain, Hartford county, State of Connecticut, have invented certain new and useful Improvements in Cylinder-Lock Construction, of which the following is a full, clear, and exact description.

My invention relates to improvements in cylinder lock construction.

In the accompanying drawings, Figure 1 is a side elevation, partly in section, of my improved cylinder lock as applied to a door. Fig. 2 is an elevation of the inner end of 15 the lock, the attaching plate and screws being removed, as well as the plug. Fig. 3 is a plan view of certain of the parts shown in Fig. 2. Fig. 4 is a rear end elevation of 20 certain of the parts shown in Fig. 1. Fig. 5 is a central longitudinal section of certain parts showing a slight modification. Fig. 6 is an end elevation of the parts shown in Fig. 5.

1 represents a part of a door, having a bore in the outer side extending partially through and of sufficient diameter to permit the cylinder case and associated parts of the cylinder lock to be inserted. This bore is continued on through the door at a somewhat reduced diameter for the purposes hereinafter described.

2 represents the shell or cylinder casing of the lock, the same containing the usual rotatable plug.

3 is the spindle which projects rearwardly from the lock and is connected with the latch or bolt (not shown) to be operated.

4 represents the face plate.

5—5—5 represent pin-tumbler passages. 40 The shell and that part thereof providing pin-tumbler passages is an integral structure, being struck up from sheet metal, the edges of said metal being offset, as at 6—6, and scalloped to provide between said scallops the aforesaid pin-tumbler passages.

The forward ends of the offset edges 6—6 are provided preferably with the lugs 7—7, which may, if desired, be connected by a rivet 8. These lugs dowel into a suitable 45 recess or passage in the rear of the face plate 4, said front plate being also bored to receive the adjacent cylindrical end of the 50 2, whereby the plate 4 may be secured permanently to said shell. The rear ends of

the offset edges 6—6 are extended to provide 55 the lugs or ears 9—9.

10 represents a rear plate, the two opposite ends of which are provided with the screw-passages 11—11 shown in Fig. 2. The plate 10 may be riveted to the ears 9—9 and 60 may be further secured to the cylinder by integral offset lugs 12—12.

As shown in the modification, Figs. 5 and 6, the only part modified therein is the rear end of the shell 2, which is spun outwardly 65 to form a ring-like flange 12^a, which performs the function of the lugs 12—12.

14 is a keeper-plate.

15 illustrates an adjusting or clamping screw, which passes through the keeper- 70 plate and into one of the screw-threaded openings 11 in the rear end-plate of the cylinder lock structure. A corresponding screw would obviously be provided for the other screw-threaded opening 11.

16—16 are wood screws, which, for convenience sake, may be provided to hold the plate 14 in proper position.

17 is an escutcheon plate, such as ordinarily used on the front of a door. 80

When the parts are all assembled, it is obvious that by setting up on the screws 15 said cylinder lock will be held securely in place within the opening at the outer side of the door and said spindle 3 will project 85 through the door to engage with such latch mechanism as may be employed, the ordinary well known spring-rim-latch being one form of such mechanism.

It will be observed that the two edges 6—6 90 of the shell 2 in which the tumbler pockets are formed, will be held together permanently more effectively than by mere rivets, since the projection formed by the ears 7—7 will take into a correspondingly shaped 95 pocket or passage in the face plate 4 so that when assembled therewith it will be impossible for the shell to spring open. So also, when the ears 9—9 are secured to the rear plate 10, a further means is provided for 100 holding said shell in its final position. As shown herein, the lugs 7—7 may be of sufficient length to pass entirely through the face plate 4 so that they may be offset or riveted, whereby said lugs will perform the 105 additional function of a rivet to tie the separate parts together. When so applied, a finishing scalp, as shown, may be added to

the face plate 4 for the purposes of ornamentation, and to cover the upset ends of the lugs 7—7.

What I claim is:

- 5 1. In a cylinder lock, a shell formed of sheet metal rolled up to form a pin cylinder plug casing, the edges of said shell being offset and scalloped to form a pin tumbler passage when brought together, a face plate and lugs at the front ends of the offset edges of the shell to secure said shell to said face plate.
- 10 2. In a cylinder lock a shell formed of sheet metal rolled up to form a pin cylinder plug casing, the edges of said shell being offset and scalloped to form a pin passage when brought together, a face plate, lugs at the front ends of the offset edges of the shell to secure said shell to said face plate, and a rear plate with lugs at the rear ends

of said offset edges of said shell to afford means of connection for said rear plate.

- 15 3. In a cylinder lock, a shell formed of sheet metal rolled up to form a pin cylinder plug casing, the edges of said shell being offset and scalloped to form a pin passage when brought together, a face plate, lugs at the front ends of the offset edges of the shell to secure said shell to said face plate, and a rear plate with lugs at the rear ends of said offset edges of said shell to afford means of connection for said rear plate, said rear plate having a screw-threaded passage, a keeper-plate and a clamping screw carried thereby and arranged to enter said screw-threaded passage.

HENRY G. VOIGHT.
